UNITED STATES PATENT OFFICE.

FRANK F. FORSHEE, OF FLINT, MICHIGAN, ASSIGNOR TO WESTINGHOUSE ELECTRIC PRODUCTS COMPANY, A CORPORATION OF MICHIGAN.

SADIRON.

Application filed November 12, 1920. Serial No. 423,562.

To all whom it may concern:

Be it known that I, FRANK F. FORSHEE, a citizen of the United States, and a resident of Flint, in the county of Genesee and State of Michigan, have invented a new and useful Improvement in Sadirons, of which the following is a specification.

My invention relates to electrically heated apparatus and particularly to electrically heated flat irons, and it has for one of its objects to provide a handle member for a flat iron which shall have a single adjustable pivotal connection to said iron.

In practising my invention I provide an electrically heated flat iron with a handle member which is adjustably and pivotally mounted on said iron and which has a plurality of positions relatively thereto. I provide a terminal member permanently secured to and mounted on said iron and I provide a single means for holding said handle and said terminal member in proper operative position on the iron. I provide also a supporting means secured to the body of the iron which is adapted to cooperate with the handle to support the iron when the same is tilted on its longitudinal axis.

Referring to the single sheet of drawings,

Figure 1 is a view, in side elevation, of a flat iron comprising the device embodying my invention with certain parts shown in section:

Fig. 2 is a view, in rear elevation, of the flat iron in its sidewise-tilted position.

Fig. 3 is a cross-sectional view, taken on the line III—III of Figure 1.

Fig. 4 is a view in plan of a part of the flat iron supporting member, and

Fig. 5 is a developed top plan view of a part of the device embodying my invention.

An electrically heated flat iron 1 comprises a bottom plate 2, a top or cover member 3 and an electrical heating element 3^a clamped between the top member 3 and the bottom plate 2. The bottom plate, heating element and the top member are held in their proper operative relation by means of a plurality of bolts or screws 4. A handle supporting member 5 is suitably secured to the top of the iron by means of the bolts 4 and comprises a flat metal strip 55 which first extends parallel to the top sur-

face of the iron and then diagonally upwards from a point a small distance inside of the rear of the iron.

A terminal block 6 of suitable insulating material is provided with screws 7 to which may be connected the terminals (not shown) of the heating element and to which may also be connected the ends of the supply conductors 8. A short tubular member 9 of lava or similar insulating material, is so arranged as to be held in its proper position inside of a thin metal cover member 10 which suitably encloses the member 9, the terminals of the heating element and the ends of the supply circuit conductors 8 and is held in place against the block 6 by means of a bolt 11.

A metal handle-mounting member 12, a developed top plan view of which is illustrated in Fig. 5, has two longitudinally and parallel extending parts 13, and a forwardly extending tongue 14 by means of which it may be secured to the body of the iron by one of the bolts 4.

Each of the parts 13 is provided with a substantially circular opening 15, in which is placed a short shaft 16. A screweye 17 is pivotedly mounted on the shaft 16. The forward edge of each of the parts 13 is made with three angularly disposed bevels for a purpose to be hereinafter set forth.

A handle member comprises a suitable handle 18 which may be made of wood, and an enclosed metal member 19 projecting slightly beyond the end of the handle and having internal screwthreads adapted to cooperate with the screwthreads on the outer end of the screweye 17. A bolt or screw 20 may be provided in the upper end of the handle 18 to secure the member 19 in its proper operative position in the handle 18. It may be noted that the handle 18 may be fixed in one of a plurality of positions by so rotating the parts 18 and 19 on the screweye 17 as to cause the handle 18 to approach, and the outer surface of the member 19 to operatively engage, the bevel edges of the parts 13 in any one of the positions shown in Figure 1.

If the handle is in the position shown in full lines in Figure 1, it may be moved to either of the positions shown by the broken lines by unscrewing the handle for a small distance, moving it into a new position and then again tightening the handle on the

screweye 17 until the outer surface of the member 19 is pressed against the bevel edges of the parts 13. While I have shown only three positions, I do not wish to be limited to the construction shown in the drawing, as I may use other similar methods which may give a larger number of operative positions.

The handle mounting member 12 is clamped against the diagonally extending part of the supporting means 5 by the screw 11, so that the terminal block 6, the member 12 and the cover member 10, together with the tubular member 9, are all held in their proper positions by means of the screw 11.

A flat iron supporting member 21 comprises a member of substantially U-shape, which may be made of resilient material. The inner end of each of the main parts of the member 21 is so bent as to form a substantially closed circle, the inner diameter of which is of such size as to permit placing therethrough the bolt 4, by means of which the supporting member 21 is held in its proper operative position on the iron 1.

The member 21 is of such dimensions, and the main parts thereof are so bent, that the connecting part thereof is a substantial distance away from, and parallel to, the side of the iron. If it is desired to place the iron in an inoperative position upon the top of an ironing board, it is only necessary to tilt around its longitudinal axis, first upon the near edge of the iron and then upon the connecting part of the member 21, until the iron rests in a sidewise-tilted position upon the outer part of the member 21 and the handle member 18.

It may be noted that the device embodying my invention provides a pivotally and adjustably mounted handle for a flat iron having only one connection therewith and provides also a normally non-removable terminal block which is held in its proper operative position on the iron by a single holding means, which, at the same time, holds the handle mounting member in its operative position. The pivotally and adjustably mounted handle provides a plurality of operative positions of the handle relative to the iron, and it may be noted that, when the handle is in the position shown in the full line of Figure 1 the hand of the operator will be in substantial alinement with the wrist and forearm, thus preventing

undue fatigue of the operator during the ironing.

The handle may be moved to a position substantially in alinement with the top surface of the iron, in which position the iron may be packed in a relatively small space. The supporting member 21 permits resting the iron upon a table in a sidewise-tilted position, with little effort on the part of the operator in placing it in this position.

Various modifications may be made on the device embodying my invention without departing from the spirit and scope thereof, and I desire that only such limitations may be placed thereon as are imposed by the prior art or are specifically set forth in the appended claims.

I claim as my invention:—

1. The combination with an electric iron, of a handle-mounting member of substantially U-shape, in cross-section, a handle-supporting member, a terminal block, a cover member for said terminal block, a single means for securing said handle-mounting member, terminal block, and terminal block cover member on said handle-supporting member, and a handle having a single adjustable connection with said handle-mounting member.

2. The combination with an electric flat iron, of a terminal block, a handle, a single adjustable and pivotal mounting for said handle, means for holding said handle in a predetermined position of adjustment relatively to said iron, and a single supporting means for both said terminal block and said handle-mounting means.

3. An electric iron comprising a body, a handle-supporting member attached thereto, a handle-mounting member, of substantially U-shape in cross-section, secured to said handle-supporting member, and a handle having a pivotal mounting in said handle-mounting member and co-operating therewith to secure the handle in any one of a plurality of operative positions on said iron.

4. An electric iron comprising a heating element, a terminal block therefor, a handle, a mounting means for supporting said handle, and a single supporting means for said handle-mounting means and said terminal block.

In testimony whereof, I have hereunto subscribed my name this 6th day of Nov., 1920.

FRANK F. FORSHEE.
